(57) **CLAIM**

I claim the ornamental design for a vehicle umbrella receptacle, as shown and described.

DESCRIPTION

FIG. 1 is a perspective view of one embodiment of a design of the present invention for a vehicle umbrella receptacle; FIG. 2 is a top view of the vehicle umbrella receptacle of FIG. 1;

FIG. 3 is a bottom view of the vehicle umbrella receptacle of FIG. 1;

FIG. 4 is a side elevation view of the vehicle umbrella receptacle of FIG. 1;

FIG. 5 is a front elevation view of the vehicle umbrella receptacle of FIG. 1; and,

FIG. 6 is a rear elevation view of the vehicle umbrella receptacle of FIG. 1.

1 Claim, 3 Drawing Sheets(56)
